UNITED STATES PATENT OFFICE.

BYRON W. PINNEY, OF LESTERSHIRE, NEW YORK.

REINFORCED-CONCRETE RAILWAY-TIE

1,045,741.

Specification of Letters Patent. Patented Nov. 26, 1912.

Application filed July 22, 1911. Serial No. 639,938.

To all whom it may concern:

Be it known that I, BYRON W. PINNEY, a citizen of the United States, residing at Lestershire, in the county of Broome and State of New York, have invented new and useful Improvements in Reinforced-Concrete Railway-Ties, of which the following is a specification.

This invention provides an indestructible cross-tie for use in the construction of railways, said tie having its body portion formed of concrete and reinforced, said reinforcement being utilized as anchoring means for the rail chairs, the latter being supplied with cushioning seats for relieving the rolling stock of excessive vibration.

The invention contemplates novel means for securing the rails to the tie, said means also serving as fastening means between the rail chairs and the reinforcement. A further purpose of the invention is the provision of clips which are adapted to interlock with the rail chairs, thereby preventing turning of the clips upon the fastening so that a single securing element may be successfully and advantageously employed.

The invention consists of the novel features, details of construction and combination of parts, which hereinafter will be more particularly set forth, illustrated in the accompanying drawings, and pointed out in the appended claims.

Referring to the drawings, forming a part of the specification, Figure 1 is a side view of a concrete cross tie for railways embodying the invention, parts being broken away to show more clearly the relative arrangement of the reinforcement and the chair. Fig. 2 is a top plan view of an end portion of the tie, the dotted lines showing the position of the rail. Fig. 3 is a section on the line *x--x* of Fig. 2. Fig. 4 is a section on the line *y--y* of Fig. 2. Fig. 5 is a perspective view of the rail chair. Fig. 6 is a perspective view of one of the clips.

Corresponding and like parts are referred to in the following description, and indicated in all the views of the drawings, by the same reference characters.

The tie embodies a body portion 1 which is formed of concrete, the same being molded in any convenient way. A beam 2 is embedded in the concrete forming the body of the tie and extends to within a short distance of each end thereof. The reinforcing beam is substantially of U-form in cross section,

although it may be of any cross sectional shape. Openings are formed in the beam at intervals in its length to admit of the concrete or plastic material forming bonds. A rail chair 3 is located near each end of the tie and is secured to the reinforcing beam 2 which serves as a firm anchorage therefor. The rail chair may be cast or formed in any manner and has a recess 4 in its under side to receive the upper portion of the reinforcing beam, the portions of the chair at the sides of the recess embracing opposite sides of the beam 2 to prevent lateral displacement of the chair. A recess 5 is formed in the upper side of the chair and extends at a right angle to the recess 4 in the under side of the chair. A cushioning plate 6 is fitted in the recess 5 and preferably consists of a block of wood which is adapted to neutralize in a measure the vibration, thereby preventing excessive wear upon the rolling stock. The end portions of the rail chair upon opposite sides of the seat 5 have openings or recesses 7 designed to receive flanges 8 of clips 9, thereby preventing movement of said clips after the same have been placed in proper position and made secure by the fastening means. The rail chairs are placed directly upon opposite end portions of the reinforcing beam 2 and are secured thereto by the same fastening means which hold the cushioning seats 6 and the clips 9 in place.

The rail chairs are embedded in the concrete or plastic material from which the tie is formed to a depth to admit of the upper surface of the cushioning seats 6 and the end portions of the rail chairs having the recesses 7 coming about flush with the upper side of the tie. The fastening means for the rail chairs consist of bolts 10 which pass through registering openings formed in end portions of the beam 2, the rail chairs, the cushioning seats and the clips, the projecting ends receiving nuts 11, whereby the parts are drawn together, thereby serving to hold the rail chairs and adjunctive parts in firm position. By having the openings formed in the end portions of the beam 2 a uniform distance apart they serve as means for properly gaging the track when constructing the same. The rail chairs are secured to the reinforcing beam 2 prior to molding the concrete or other plastic material about the same to form the composite tie.

The clips 9 may be cast, forged, or constructed in any manner and are substan-

tially of L form in edge view, the main portion of the clip adapted to extend over the tie with its inner end overlapping the foot of the rail and the pendent flange 8 entering the opening or recess 7. Each bolt passes through an opening of the clip, the latter being prevented from turning by reason of the flange 8 entering the opening 7. By removing the nuts 11 the clips may 10 be displaced, thereby admitting of removal of the rail.

From the foregoing description, taken in connection with the accompanying drawings, the advantages of the construction and 15 of the method of operation will be readily apparent to those skilled in the art to which the invention appertains, and while I have described the principle of operation of the invention, together with the device which 20 I now consider to be the embodiment thereof, I desire to have it understood that the device shown is merely illustrative, and that such changes may be made when desired as are within the scope of the claims ap- 25 pended hereto.

A brace 12 is arranged beneath the beam 2 and is clamped thereto at its ends by means of the bolts 10. The middle portion 30 of the brace is deflected downwardly and being embedded in the concrete forms a truss. The inner or lower ends of the bolts 10 are threaded into openings formed in the brace 12, as shown most clearly in Fig. 3.

Having thus described the invention what 35 is claimed as new, is:—

1. A railway tie comprising a body of concrete, a reinforcing beam embedded in the body of the tie, rail chairs embedded 40 in the tie and mounted upon end portions of the reinforcing beam, each rail chair

having portions embracing opposite sides of the reinforcing beam and having a depression in its top side, a cushioning plate 45 fitted in the depression in the top side of the rail chair, clips having their outer ends interlocking with end portions of the rail chairs and having their inner ends engaging over the foot of the rail, and fastenings 50 passing through registering openings 50 formed in the clips, cushioning plates, rail chairs and reinforcing beam.

2. A railway tie comprising a body of concrete, a channel beam embedded in the tie, rail chairs mounted upon end portions 55 of the reinforcing beam and having side portions embracing opposite sides of said beam, each rail chair having a depression in its top side and elongated openings in its end portions at the sides of the depression, cushioning plates mounted in the depressions of the rail chairs, clips having pendent flanges at their outer ends to enter the elongated openings of the rail chairs and having their inner ends adapted to 60 engage over the foot of the rails, a brace of substantially truss form embedded in the tie with its end portions in contact with the before mentioned reinforcing beam, and bolts having their inner ends threaded into 65 the said brace and passing through registering openings formed in the reinforcing beam, rail chairs, cushioning plates and clips and having nuts threaded upon their outer ends.

In testimony whereof I affix my signature in presence of two witnesses.

BYRON W. PINNEY.
